BY Victor J. Crane
ATTY.

UNITED STATES PATENT OFFICE.

PATRICE H. HICKEY, OF HAPPY CAMP, CALIFORNIA.

DESIGN FOR A TIME INDICATOR.

Application filed January 23, 1928. Serial No. 24,990. Term of patent 14 years.

To all whom it may concern:

Be it known that I, PATRICE H. HICKEY, a citizen of the United States of America, residing at Happy Camp, in the county of Siskiyou and State of California, have invented a new, original, and ornamental Design for a Time Indicator, of which the following is a specification, reference being had to the accompanying drawing, forming a part thereof.

The figure is a front elevation of my design.

I claim:—

The ornamental design for a time indicator substantially as shown.

PATRICE H. HICKEY.
